INVENTOR.

UNITED STATES PATENT OFFICE.

JOSEPH C. DUNHAM, OF OKLAHOMA, OKLAHOMA.

WINDOW.

1,348,127.

Specification of Letters Patent. Patented July 27, 1920.

Application filed December 30, 1919. Serial No. 348,437.

To all whom it may concern:

Be it known that I, JOSEPH C. DUNHAM, a citizen of the United States, residing at Oklahoma, in the county of Oklahoma and State of Oklahoma, have invented certain Improvements in Windows, of which the following is a specification, reference being had to the accompanying drawings.

The object of the invention is to prevent passage of air and dust between the jamb and sash of a window.

Figure 1 of the drawings is an elevation view of a window.

Fig. 2 is an enlarged sectional view taken on the line 2—2 of Fig. 1.

Fig. 3 is a perspective view of the upper end of a metal strip.

In Fig. 2 the metal strips are shown of exaggerated thickness and their cross-section shading is done in solid black; the cross-section of the other parts of the figure being nearly omitted.

Like characters of reference designate like parts in all the figures.

The window shown includes the usual outer casing 5, jamb 6, parting-stop 7, inner stop 8, inner casing 9, upper sash 10, and lower sash 11; these parts being well known in the art of building.

In carrying out the object stated, the improved strip 12, best shown in Fig. 3, is provided and interposed between each of the sashes 10 and 11 and the jamb 6.

In cross-section this strip 12 is so shaped that its back surface along a longitudinal line rests against the surface of the jamb 6 and its edges 13 and 14 rest against the sash, the strip being under elastic tension to engage said jamb and sash with an air-tight fit.

The longitudinal line above referred to is, in this instance, nearer the edge 13 of the strip 12, and along said line the strip is curved or beaded back toward the jamb 6 on short radius, as at 15, so as to have a more air-tight bearing against the jamb 6 than it would otherwise have; and for the same reason the edges 13 and 14 of the strip are beaded toward the sash, as at 16.

In addition to the rearwardly-extending bead 15 intermediate the edges of the strip

12, a second rearwardly-extending bead 17 is formed close to and parallel with said bead 15, this bead 17 standing normally out of contact with the jamb 6 when considerable space is left between the sash and jamb as in the case of the upper sash in Fig. 2; but when the space between the sash and jamb is reduced, as in the case of the space between the lower sash and the jamb in Fig. 2, the straightening of the strip out in cross-section brings the second or added bead 17 into contact with the jamb.

This arrangement affords the strip 12 additional bearing against the jamb 6 when compressed into smaller space and under increased tension.

In addition to the forwardly-extending bead 16 at each edge of the strip 12, a second forwardly-extending bead 18 is formed close to and parallel with said bead 16 at the edge 14, this added bead 18 standing normally out of contact with the sash when the strip is not closely compressed; but when the space between the jamb and sash is reduced the straightening of the strip in cross-section brings the added bead 18 into contact with the sash.

This arrangement affords the strip 12 additional bearing against the sash when compressed into small space and under increased tension and thereby prevents the beads 16 from weaving the sash too deeply.

The strip 12 may be secured in place by nails 19 which may be driven through the bead 15 and into the jamb 6.

Having thus described the invention, I claim:

1. A strip of elastic sheet material adapted to be interposed between a sash and jamb, the strip having two longitudinal beads projecting toward the jamb, the strip being so shaped in cross-section that when compressed into a given space only one of the beads contacts the jamb but when compressed into smaller space the second bead is brought into contact with the jamb.

2. A strip of elastic sheet material adapted to be interposed between a sash and jamb, the strip being so shaped in cross-section that its back surface along a longitudinal line contacts the jamb and its edges contact

the sash, the back of the strip along said line being provided with a bead which contacts the jamb, the strip being also provided with a second bead close to and parallel with the first-named bead, the strip being so shaped in cross-section that when compressed into a given space only the first-

named bead contacts the jamb but when compressed into smaller space the second bead is brought into contact with the jamb. 10

Witness my hand this 15 day of December, 1919.

JOSEPH C. DUNHAM.
